UNITED STATES PATENT OFFICE

94,156

DESIGN FOR PLIERS

Howard H. Manning, Meadville, Pa., assignor to
Champion De Arment Tool Company, Mead-
ville, Pa.

Application October 27, 1933, Serial No. 49,570

Term of patent 14 years

To whom it may concern:

Be it known that I, Howard H. Manning, a citizen of the United States, residing at Meadville, county of Crawford, and State of Pennsylvania, have invented a new, original, and ornamental Design for Pliers, of which the following is a specification, reference being had to the accompanying drawing, forming a part thereof, and in which—

Figure 1 is a perspective view illustrating one side of the pliers, and

Figure 2 is a perspective view illustrating the other side of the pliers.

I claim:

The ornamental design for pliers as shown.

HOWARD H. MANNING.
